UNITED STATES PATENT OFFICE.

ALLYN B. WALTON, OF LORAIN, OHIO, ASSIGNOR TO THE NATIONAL VAPOR STOVE AND MANUFACTURING COMPANY, OF SAME PLACE.

DESIGN FOR A CASING FOR ARC-LAMPS.

SPECIFICATION forming part of Design No. 33,823, dated January 1, 1901.

Application filed December 5, 1900. Serial No. 33,845. Term of patent 14 years.

To all whom it may concern:

Be it known that I, ALLYN B. WALTON, a citizen of the United States, residing at Lorain, in the county of Lorain and State of Ohio, have invented and produced a new and original Design for Casings for Arc-Lamps, of which the following is a specification, reference being had to the accompanying drawing, forming part thereof.

10 In the accompanying drawing the single figure presented shows a perspective elevation of my new and original design in casings or inclosures for arc-lamps, and the leading and material features of the design are found especially in the lower portions thereof, which contribute to the luster and illuminating effects of the lamp, although the design as such is necessarily incomplete, except as a unitary article comprising the casing as a whole.

20 As thus shown in the drawing, the complete design is embodied in several distinct and essential features consisting in the body *a*, which is of substantially cylindrical outline with attractive surface ornamentation, the 25 cap or crown *b*, mounted on body *a* and deco-

rated with a series of openings *c* around the same and having a central projection *e* at its top, and the lower portion of said casing comprising a substantially acorn-shaped pendant *d*, which in a sense is an extension or prolongation of body *a*, but is intervened by an ornamental rim *g*, resembling in appearance the straight rim of a hat, though it slopes or curves downward somewhat toward its outer edge and is especially conspicuous for its lustrous underside. The pendant cone *d* being 30 irradiant harmonizes with the brilliancy of said rim, and the effect is especially attractive under the glow of illumination.

Having described my invention, what I 40 claim as new, and desire to secure by Letters Patent, is—

The design for a casing for arc-lamps, substantially as herein shown and described.

Witness my hand to the foregoing specification this 21st day of November, 1900.

ALLYN B. WALTON.

Witnesses:

G. A. RESCH,
J. J. MAHONEY.
